UNITED STATES PATENT OFFICE.

ARTHUR ROBERTS, OF EVANSTON, ILLINOIS.

REGENERATIVE COKE-OVEN.

1,313,207.

Specification of Letters Patent. Patented Aug. 12, 1919.

Application filed January 3, 1916, Serial No. 69,997. Renewed November 8, 1918. Serial No. 261,739.

To all whom it may concern:

Be it known that I, ARTHUR ROBERTS, a citizen of the United States, residing at Evanston, county of Cook, and State of Illinois, have invented certain new and useful Improvements in Regenerative Coke-Ovens, of which the following is a specification.

The present invention has reference to certain improvements in regenerative coke ovens; that is, coke ovens which are so constructed that the incoming air may be preheated by regeneration. The invention relates generally to a construction of this class in which there are provided regenerators for each group of burners, so that the several groups of burners are made independent of each other to the extent that the preheating of the air for each group of burners is independent of the preheating of the air for the other burners. There have been devised in the past oven constructions in which this result has been secured, but, as far as I am aware, all of said constructions have been open to the objection that the regenerators have been located close to or even between and in contact with the oven heating walls. This has made it necessary to separate the carbonizing chambers an additional distance from each other sufficient to accommodate the regenerators, thus greatly lengthening the overall dimensions of the bench of ovens, which, except for this reason, might be considerably shortened. Furthermore, when the regenerators are placed between the carbonizing chambers, said chambers are necessarily subjected to periodical fluctuations of temperature, according to the heating and cooling of the regenerators. This results in an uneven operation of the ovens, so that it is difficult, if not impossible, to secure a perfectly uniform carbonizing effect, and in addition to the foregoing objection, the oven walls are subjected to violent and severe stresses due to expansion and contraction. These stresses rapidly open up seams in the oven walls, so that leakage from the carbonizing chambers ensues, with a resulting loss of gas and by-products.

One of the objects of the present invention is to so arrange the several regenerator structures that they may be set at some other point than between the carbonizing chambers, thus making it possible to secure the desired regeneration without in any man-

ner lengthening the bench of ovens. At the same time it is desired to so locate the regenerators that they may occupy a space which is ordinarily wasted, thus economizing in space and cost of construction.

Another feature of the invention has reference to the placing of the regenerators at such locations with respect to the heating walls that short and direct gas passages may be secured between the burners and regenerators. Not only will this result in the production of a more compact structure, but also it will reduce the loss of heat and variation of temperature between the regenerators and the burners.

Another object of the invention is to so arrange the structure that whenever desired any set of regenerators may be isolated from the remaining regenerators, thus permitting them to be removed or replaced or cleaned with a minimum of interruption to the service of the bench as an entirety.

Other objects and uses of the invention will appear from a detailed description of the same which consists in the features of construction and combinations of parts hereinafter described and claimed.

In the drawings:

Figure 1 shows a longitudinal section through a heating wall with its burners, and through the corresponding regenerators, being taken on line 1—1 of Fig. 3, looking in the direction of the arrows;

Fig. 2 shows a longitudinal section through the central portion of the carbonizing chamber, being taken on line 2—2 of Fig. 3, looking in the direction of the arrows;

Fig. 3 shows a cross section through three heating walls and carbonizing chambers of a bench, and through the corresponding regenerators, being taken on the line 3—3 of Fig. 1, looking in the direction of the arrows, but on an enlarged scale;

Fig. 4 shows a fragmentary horizontal section corresponding to Fig. 3, but on a considerably enlarged scale, being taken on the line 4 of Fig. 1, looking in the direction of the arrow;

Fig. 5 shows a fragmentary horizontal section through one of the air passages and two of the burners, being taken on the line 5—5 of Fig. 1, looking in the direction of the arrows, but on an enlarged scale;

Fig. 6 shows diagrammatically a plan view of the foundation flues for the waste

gases, a portion of the flues being broken away so as to shorten up the figure;

Fig. 7 shows a detail plan view of one of the blocks used in the construction of the heating wall illustrated in the several figures;

Fig. 8 shows a detail side view corresponding to Fig. 7;

Fig. 9 shows a detail plan view of one of the keystone blocks; and

Fig. 10 shows a side view corresponding to Fig. 9.

In the several figures I have shown a coke oven construction embodying the general type of heating wall disclosed in my Letters Patent of the United States, No. 1,132,685, issued to me March 23, 1915. In that type of construction, the heating wall is built up from blocks having certain of their side and horizontal faces recessed, so that, when the several blocks are set together, they provide a mesh of tortuous or zigzag passages through which the hot gases travel toward the point of exit. More particularly, in this case I have shown a type of burner and heating wall construction disclosed in a co-pending application for Letters Patent of the United States, for improvements in burners, executed by me of even date herewith filed January 3, 1916, as Serial No. 69,999. I have shown this type of heating wall and burner construction in the present case largely as a matter of convenience, inasmuch as it will be understood that the features of the present invention have reference particularly to the arrangement of the regenerators.

In the particular construction illustrated, the burners 11 supply the heating gases to the tortuous passages of the heating wall 12. Each heating wall is provided with a row of burners, and there may be as many heating walls as desired in the bench. The air for each group of burners is supplied to said group by means of a horizontal passage 13 from which the air passes down around each burner to be mixed with the gas supplied through the central portion of the burner tube at the lower end thereof.

Referring particularly to Fig. 3, it will be seen that I have illustrated only a single heating wall 12 between each pair of carbonizing chambers 14 and 15. This, however, is done largely as a matter of convenience, inasmuch as each carbonizing chamber might be provided with two heating walls if desired, in which case there would be located two heating walls between each pair of carbonizing chambers. It will be understood that as far as the features of the present invention are concerned, the use of one or more heating walls between each pair of carbonizing chambers is a matter of convenience.

Extending upward in each wall are up-

takes 16 and 17. The upper ends of these communicate with the corresponding horizontal passage 13, so that the air may be delivered up through either of the passages 16 or 17 as desired. Beneath each heating wall is a horizontal channel 18 within which the spent gases from the entire heating wall are collected.

At whatever spacings may be desired, there are provided the regenerator structures 19, 20, 21, and 22. These regenerator structures are located in pairs, the regenerators of each pair standing in horizontal alignment and being separated by the horizontal partition 23. At their back ends, the regenerators 19 and 20 are connected by a vertical passage 24, and similarly the back ends of the regenerators 21 and 22 are connected by a vertical passage 25. In the particular arrangement illustrated, there is a complete set of regenerators 19, 20, 21, and 22 corresponding to each heating wall, but, if desired, one complete set of said regenerators might supply or operate for two or more heating walls, this being largely a matter of convenience in construction. As shown in Fig. 3, the several sets of regenerators are separated by the partitions 26, which partitions are located immediately beneath the soles of the ovens, so that the loads of carbonizing material are directly carried by said partitions. This insures a direct transmission of the load to the foundation without having to pass said load through trusses or arches.

Extending lengthwise beneath the sides of the bench are the tunnels 27 and 28. At one end these tunnels are connected by a cross connection 29 which leads to the stack or exhaust fans by a connection 30. The dampers 31 and 32 permit of the tunnels to be isolated from the cross connection 29 as desired. The air connections 33 and 34 lead into the tunnels 27 and 28 so that fresh air may be delivered to either of said tunnels under pressure.

Adjacent to the front ends of the regenerators 20 and 22 are the vertical chambers or passages 35 and 36, respectively, while adjacent to the front ends of the regenerators 19 and 21 are the vertical chambers or passages 37 and 38 respectively. The upper ends of the passages 37 and 38 communicate with the end portions of the channel 18 and with the lower portions of the up-takes 16 and 17 by means of the openings 39 and 40. Above the openings 39 and 40 are the slideable dampers 41 and 42 which may be moved into the two extreme positions illustrated at the ends of Fig. 1. At one side of said figure the damper 41 is shown as being moved fully in, whereas the damper 42 is shown as being drawn fully out. In the positions mentioned, the damper 41 isolates the opening 39 from the channel 18, but connects said

opening to the lower end of the up-take 16; whereas in the position of the damper 42 said damper isolates the opening 40 from the lower end of the up-take 17, and connects 5 the opening 40 to the channel 18.

The vertical passages or chambers 35 and 36 communicate respectively with the tunnels 27 and 28, but whenever it is desired to cut out any particular oven or set of regenerators, this may be done by closing the dampers 43 and 44.

The operation of the structure will now be readily understood. Assuming that the dampers 41 and 42 stand in the positions 15 illustrated in Fig. 1, the damper 31 should be closed, the damper 32 opened, air supplied to the connection 33, and the connection 34 closed. Under these circumstances, the fresh air will be delivered from the connection 33 into the tunnel 27, and thence it will pass up by way of the regenerators 20 and 19, where it will be heated, said regenerators having been previously heated by spent gases. From the regenerator 19, the 20 hot air will pass up by way of the opening 39 through the up-take 16 and into the horizontal connection 13. From the horizontal connection, hot air will be supplied to the various burners, uniting with the gas, and 25 passing down through the heating wall. The spent gas from the heating wall will collect in the channel 18, pass through the opening 40 into the connection 38, and thence by way of the regenerators 21 and 22 into the 30 flue 28. The damper 32 being opened, the spent gas will be discharged from said flue through the connection 30 to the stack or fan as desired. On the reverse operation, the positions of the dampers 41 and 42 will 35 be reversed, the positions of the dampers 31 and 32 will be reversed, the air connection 33 will be closed, and air will be supplied into the connection 34.

It will be seen from an examination of 45 Fig. 1 in particular, that each of the regenerators 19, 20, 21 and 22 is composed of a series of separated stacks or piles of checker-work which stand independently of each other within the several chambers. By the 50 use of this arrangement, the longitudinal expansions and contractions will be taken care of in the several piles, and on account of the relatively small size of each of these piles, the amount of expansion and contraction to be 55 thus controlled will be comparatively small, or even negligible. It will be seen also from an examination of this construction that it is possible to secure the desired regenerator capacity beneath each heating wall by making 60 the regenerator of the desired height. It will frequently happen that the vertical distance or height available for the accommodation of the necessary regenerator capacity in a width substantially equal to that 65 of the heating wall is more than sufficient,

in which case the full regenerator capacity can be secured even where there is but a single heating wall between each pair of carbonizing chambers, and without the necessity of increasing the length of the bench. 70

While I have herein shown and described only a single construction or embodiment of my invention, still it will be understood that many changes of form and arrangement may be made without departing from its 75 spirit.

I claim:

1. In a bench of coke ovens having heating walls, the combination with each heating wall of a pair of regenerators beneath 80 said heating wall, a plurality of burners in the upper portion of each heating wall, an air passage in each heating wall connecting with the burners thereof, a riser connecting with each end of each of said air passages, a spent gas channel beneath each heating wall, a connection from the upper portion of each regenerator to the lower portion of the adjacent riser and to the adjacent end of the spent gas channel, a valve for each 85 of said connections to isolate the connection either from the riser or from the spent gas channel, a tunnel beneath each side of the bench of ovens, a connection between the lower end of each regenerator and the adjacent 90 tunnel, means for controlling the delivery of spent gas from each tunnel, and means for controlling the delivery of air into each tunnel. 95

2. The combination with a bench of coke 100 ovens, each oven having a heating wall, of a plurality of burners in the upper portion of each heating wall, a common air connection for feeding all of said burners, a riser connected to each end of said air connection, a spent gas channel beneath each heating 105 wall, a regenerator beneath each end of each heating wall, a connection from the upper portion of each regenerator to the adjacent end of the spent gas channel and to the adjacent riser, a valve for isolating said connection either from the riser or from the spent gas channel, a tunnel beneath each side of the bench of ovens, connections between each tunnel and lower portions of the 110 adjacent regenerators, means for controlling the delivery of spent gas from each of said tunnels, and means for controlling the delivery of air into each of said tunnels. 115

3. In a bench of coke ovens, the combination with a plurality of heating walls of burners in the upper portion of each heating wall, a common connection for delivering air to all of the burners of each heating wall, a riser communicating with each end 125 of each of said connections, a spent gas channel beneath each heating wall, a pair of regenerators beneath each heating wall, a connection from the upper portion of each regenerator to the adjacent end of the spent 130

gas channel and to the adjacent riser, a valve for isolating each of said connections either from the spent gas channel or from the riser, a tunnel beneath each side of the bench of 5 ovens, and a connection between the lower portion of each regenerator and the adjacent tunnel.

4. In a bench of coke ovens, the combination with a plurality of heating walls of 10 burners in each of said walls, a common connection for delivering air to the burners of each wall, a spent gas channel for receiving spent gas from each wall, a pair of regenerators beneath each wall, a connection from 15 the upper portion of each regenerator to the corresponding spent gas channel and to the corresponding air connection, means for isolating each of said connections either from the spent gas channel or from the air connection, a tunnel beneath each side of the bench 20 of ovens, and a connection between the lower portion of each regenerator and the adjacent tunnel.

5. In a bench of coke ovens, the combination with a plurality of heating walls of 25 burners for each heating wall, a spent gas channel for each heating wall, a pair of regenerators beneath each heating wall, each regenerator being of a width less than the 30 distance between the center lines of two adjacent heating walls, a connection from the upper portion of each regenerator to the adjacent end of the corresponding spent gas channel and the air connection, means for 35 isolating each of said connections either from the air connection or from the spent gas channel, a tunnel beneath each side of the bench of ovens, and a connection between each tunnel and the lower portions of 40 the adjacent regenerators.

6. In a bench of coke ovens, the combination with a plurality of heating walls of 45 burners in each of said heating walls, a spent gas channel for receiving spent gas from each of said heating walls, a pair of regenerators in the lower portion of the bench of ovens corresponding to each heating wall, each pair of regenerators having a dimension in the direction of the length of 50 the bench less than the distance between the center lines of adjacent heating walls, connections from the upper portion of each regenerator to the corresponding spent gas channel and to the corresponding burners, 55 means for isolating each of said connections either from the spent gas channel or the burners, a tunnel beneath each side of the bench of ovens, and a connection between each tunnel and the lower portions of the 60 adjacent regenerators.

7. In a bench of coke ovens, the combination with a plurality of heating walls of 65 burners for each heating wall, a spent gas channel for each heating wall, a pair of regenerators beneath each heating wall, each

pair of regenerators having a dimension in the direction of the length of the bench of ovens less than the distance between the center lines of adjacent heating walls, and each pair of regenerators being of vertical dimension suitable to give a desired regenerating capacity, a connection from the upper portion of each regenerator to the corresponding spent gas channel and to the corresponding burners, means for isolating each 70 of said connections either from the spent gas channel or from the burners, a tunnel beneath each side of the bench of ovens, and connections between the lower portions of the regenerators and the adjacent tunnels. 75

8. The combination with a plurality of coke ovens of heating walls between the carbonizing chambers of said ovens, burners for each heating wall, a spent gas channel for each heating wall, a pair of regenerators 80 beneath each heating wall, vertical partitions between the regenerators of adjacent heating walls, said partitions serving also to support the carbonizing chambers, a connection from the upper portion of each regenerator to the corresponding spent gas channel and the corresponding burners, means for isolating each regenerator either from the spent gas channel or from the burners, and air connections for the delivery of 85 air to the lower portions of the regenerators. 90

9. The combination with a plurality of coke ovens of heating walls between the carbonizing chambers of the ovens, burners in each heating wall, a spent gas channel for 95 each heating wall, a pair of regenerators beneath each heating wall, each pair of regenerators having a dimension in the direction of the length of the bench of ovens less than the distance between the center lines of adjacent 100 heating walls, and having a vertical dimension suitable to give a desired regenerator capacity, a connection from the upper portion of each regenerator to the corresponding spent gas channel and the corresponding burners, means for isolating each regenerator either from the spent gas channel or from the burners, vertical partitions between adjacent regenerators and beneath the carbonizing chambers, and air connections for the delivery of air to the lower 105 portions of the regenerators. 110

10. The combination with a plurality of coke ovens having carbonizing chambers, heating walls, and burners for the heating walls, of groups of regenerators beneath the opposite ends of the coke ovens, a common connection for the delivery of air to all of the burners of each heating wall, and connections from one regenerator of each group 115 to each of said common connections. 120

11. In a bench of coke ovens, the combination with a plurality of heating walls, and burners for each heating wall, of a common connection for the delivery of air to all of 130

the burners of each heating wall, a regenerator under each end of each heating wall, and connections from each of said regenerators to the common connection of the corresponding heating wall.

12. In a bench of coke ovens, the combination with a plurality of heating walls, and burners for each heating wall, of a spent gas delivery connection beneath each heating wall, a common connection for the delivery of air to all of the burners of each heating wall, a regenerator beneath each end of each spent gas connection, connections from each regenerator to each of said common connections and to each of said spent gas connections for each heating wall, and dampers for controlling communication between each regenerator and the corresponding common connection and the corresponding spent gas connection.

13. In a bench of coke ovens, the combination with a plurality of heating walls, and burners for each heating wall, of a common connection for the delivery of air to all of the burners of each heating wall, a spent gas connection for the delivery of spent gas from each heating wall, a regenerator beneath each end of each heating wall, connections from each regenerator to the aforementioned common air connection and to the aforementioned spent gas connection, and dampers for controlling the communication of each regenerator with the common air connection and the spent gas connection.

14. In a bench of coke ovens, the combination with a plurality of heating walls, and burners for each heating wall, of a common connection for the delivery of air to all of the burners of each heating wall, a spent gas connection for the delivery of spent gas from each heating wall, a regenerator for each end of each heating wall, connections from each regenerator to the aforementioned

tioned common air connection and to the aforementioned spent gas connection, and means for controlling communication from each regenerator to the common air connection and to the spent gas connection.

15. In a bench of coke ovens, the combination with a plurality of heating walls, of a common connection for each heating wall for the delivery of air to all portions thereof, a regenerator under each end of each heating wall, and connections from each of said regenerators to the common connection of the corresponding heating wall.

16. In a bench of coke ovens, the combination with a plurality of heating walls, of a common connection for each heating wall for the delivery of air to all portions thereof, a regenerator for each end of each heating wall, and connections from each of said regenerators to the common connection of the corresponding heating wall.

17. In a bench of coke ovens, the combination with a plurality of heating walls, of a common connection for each heating wall for the delivery of air to all portions thereof, a pair of regenerators for each of said common connections, and a connection from each of said regenerators to the corresponding common connection.

18. In a bench of coke ovens, the combination with a plurality of heating walls and burners for each heating wall, of a common connection for each heating wall for the delivery of air to all of the burners of the same, a pair of regenerators for each common connection, and connections from the regenerators to the corresponding common connection.

ARTHUR ROBERTS.
